(57) **CLAIM**

The ornamental design for an automated actuator device, as shown and described.

DESCRIPTION

FIG. 1 is a top-front-left perspective view of an automated actuator device showing my new design;

FIG. 2 is a bottom-rear-right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is an enlarged left elevational view thereof; and,

FIG. 8 is an enlarged right elevational view thereof.

The broken line showing an extensible member in FIGS. 1 through 6 and 7; a display screen in FIGS. 1 and 5; and an internal cavity within the actuator casing in FIGS. 2 and 8 is included for the purpose of illustrating environmental structure and forms no part of the claimed design.
